COMBINED ERASER AND BRUSH

Robert C. Heffernan, Northport, N. Y., assignor to Eberhard Faber Pencil Company, Kings County, N. Y., a corporation of New York

Application June 9, 1955, Serial No. 36,437

Term of patent 14 years

(Cl. D74—7)

Fig. 1.

Fig. 2.

Fig. 3.

Fig. 1 is a side elevational view of a combined eraser and brush showing my design;

Fig. 2 is an end elevational view thereof; and

Fig. 3 is a top plan view thereof.

The essential features of my design reside in the portions shown in solid lines on the drawing.

I claim:

The ornamental design for a combined eraser and brush, substantially as shown and described.
